Robert Y. Allen, Pacific Palisades, and Melvin Shaw, Beverly Hills, Calif., assignors to National Broadcasting Company, Inc., a corporation of Delaware

Application June 4, 1949, Serial No. 3,066

Term of patent 14 years

(Cl. D34—4)

To all whom it may concern:

Be it known that we, Robert Y. Allen and Melvin Shaw, citizens of the United States, residing at Pacific Palisades and Beverly Hills, California, respectively, have invented a new, original, and ornamental Design for a Puppet, of which the following is a specification, reference being had to the accompanying drawing, forming part thereof.

We claim:

The ornamental design for a puppet, as shown.

ROBERT Y. ALLEN.
MELVIN SHAW.
